LOOSE-LEAF BINDER

Edward F. Buenger, Oak Park, Ill., assignor to
 Wilson-Jones Company, Chicago, Ill., a corporation of Massachusetts

Application March 1, 1939, Serial No. 259,149

5 Claims. (Cl. 281—29)

This invention relates to a loose-leaf binder and more particularly to a binder having a concealed metal hinge.

It is an object of this invention to provide means for covering the metal hinge of a loose-leaf binder to prevent scratching or marring of furniture upon which the binder may be handled. It is a further object of this invention to provide simple and efficient means for securing flaps extending from the covers to the binder back. Other objects of this invention will become apparent upon reading the following description, taken in conjunction with the accompanying drawings, in which

15 Figure 1 is a fragmentary perspective view of various parts of my improved binder in disassembled position;

Figure 2 is a perspective view of the binder in closed position;

20 Figure 3 is a cross sectional view taken through one of the flap retaining members; and

Figure 4 is a fragmentary cross sectional view of the binder showing the flap retaining member in elevation.

25 In the drawings, the reference numeral 2 indicates a rounded back member along the opposite longitudinal edges of which a pair of strips 3 is welded or riveted. The strips 3 are provided with a plurality of hinge lugs 4 spaced along the inner

30 edge of each strip in pairs. A link 5 having its opposite edges curled to form hinge lugs 6 and 7 is positioned between each pair of hinge lugs 4 and is pivotally secured thereto by means of hinge pintles 8 which pass through the hinge lugs 4 and

35 6. Each link 5 is provided with a prong or tine 9 for a purpose to be hereinafter described. A strip 10 of leather, fabric, or any other suitable material, is positioned over the outer surface of the rounded back member 2 and projects beyond the

40 longitudinal edges thereof so that it can be folded over on the strip 3 and extend under the links 5 so as to be engaged by the prongs 9.

A cover member 11 is adapted to be secured to the back member by means of a hinge plate 12 secured to the cover and providing a plurality of hinge lugs 13 adapted to be aligned with the hinge lugs 7. The sheet retaining mechanism, which is not shown in detail because it is conventional structure, includes a flat back member 14 having hinge lugs 15 adapted to be aligned with the hinge lugs 7 and 13 to receive a hinge pintle 16. The flat back 14 is provided along its longitudinal edges with a pair of sheaths 17 which are notched, as indicated at 17', so that pintles 18, 55 slidably secured in said sheaths, may engage posts

19, upon which sheets 20 are impaled, to retain said sheets in the binder.

The outer surface of the cover 11 is covered with a sheet 22 of material harmonizing with the strip 10. A flap 23 of similar material is secured to the cover and projects from its hinge edge. In assembling the binder the links 5 are swung inwardly around the hinge 8 and the edges of the strip 10 and the flaps 23 are positioned over the strips 3. The links 5 are then swung outwardly around the hinge 8 so as to position the links 5 over the edges of the strip 10 and the flaps 23. The flat back member 14 is then positioned over the rounded back member 2 and the links 5 to align the hinge lugs 15 with the hinge lugs 7 and 13. The pressure of the edges of the flat back member 14 adjacent the hinge lugs 15 against the links 5 causes the prongs 9 to dig into the edge of the strip 10 and the flap 23, as shown in Figure 3. The strips 3 are apertured, as indicated at 3', in alignment with the prongs 9 to make the engagement of the prongs with the edge of the strip 10 and the flap 23 more secure. When the hinge pintles 16 are inserted into the hinge lugs 7, 13 and 15 the parts are securely held together, and the hinges are neatly covered by the flaps 23 so that an attractive appearance is attained and the hinges cannot scratch or mar any furniture upon which the binder may be handled.

Although I have described one embodiment of my invention in detail, it will be understood that the description thereof is illustrative, rather than restrictive, as many details may be modified or changed without departing from the spirit or scope of the invention. Accordingly, I do not desire to be restricted to the exact details of construction described, except as limited by the appended claims.

I claim:

1. In a loose-leaf binder, a back member, a plurality of hinge lugs rigidly secured to said back member, a plurality of links pivoted to said hinge lugs, and a cover member secured to said links.

2. In a loose-leaf binder, a back member, a plurality of links pivotally secured to the inner surface of said back member, a cover member hinged to said links, and a flap extending from said cover member and secured between said links and said back member.

3. In a loose-leaf binder, a back member, a plurality of links secured to said back member, a cover member hingedly secured to said links, a flap projecting from said cover member to cover said hinge, and means on said links for engaging said flap to hold it over said hinge.

4. In a loose-leaf binder, a back member, a plurality of links pivotally connected to the inner surface of said back member, a cover member hinged to said links, and a flap extending between said links and the inner surface of said back member from said cover member, each of said links having a prong engaging said flap to hold said flap between said links and said back member.
5. In a loose-leaf binder, a flat back member,

a cover member, said flat back member and said cover member being provided with a plurality of aligned hinge lugs, a hinge pintle passing through said hinge lugs to secure said cover member and said flat back member together, and a plurality of links mounted on said hinge, said links being adapted to secure a rounded back member to said flat back member and said cover. 5

EDWARD F. BUENGER. 10
